6 Claims. (Cl. 229—16)

This invention relates to cartons and more particularly to top closures for cartons. It also relates to one piece hardboard or corrugated cardboard blanks, adapted to be folded and erected to form such cartons.

Cartons formed of hardboard or corrugated cardboard and having side walls, a bottom and top closure means and an interior assembly to divide such carton into a plurality of article receiving compartments are well known. However, most such cartons have been provided with at least a pair of co-operating top closure flaps glued together in co-operating relationship with each other. Obviously, such top closure flaps have had to be torn apart in order to obtain access to the contents of the carton. While cartons having such top closure flaps have not proved to be too disadvantageous to the consumer, they have, nevertheless, materially added to the cost of the carton due to the low salvage value of used cartons.

Obviously, it is desirable to provide a carton which is reusable, i.e. a multi-trip carton. This, then, is a carton which can be reused several times by the bottler before its life is terminated.

It is the practice in certain countries to sell bottled beer to the consumer, the bottles being packaged in the above-mentioned type of container. Beer is preferably packaged in darkened glass bottles and the bottles packed in containers provided with a top closure, because it was found that beer, when subjected to light, whether it be natural or artificial, and even for a short time was subject to undesirable photo-chemical changes. Beer so effected is known in the trade as "light struck" and, although not injurious to humans, it is very objectionable. Consequently, it will be appreciated that bottles containing beer should not be subjected to light until required for actual consumption. After the consumer has torn open the top flaps in order to obtain access to the bottles, and has consumed the contents of the bottles, he normally returns the empty bottles in the container to the retailer. The retailer then returns the container, together with the empty bottles to the brewer or wholesaler. Upon receipt of such used container, the brewer extracts the empty bottles mechanically. Thereafter, the brewer removes the interior assembly of mutually transverse partitions from the carton in order to reclaim the assembly if it is relatively undamaged. He then disposes of the shells as used cartons or as baled scrap paper. In this fashion, the brewer obtains some return of salvage value.

Accordingly, a main feature of this invention is the provision of a carton, formed of cardboard, corrugated or otherwise, and having side walls, end walls, a bottom, and provided with such top closure means that it is capable of several trips as a multi-trip carton before its effective life is terminated.

A preferred feature of this invention is the provision of a three piece carton formed of cardboard, corrugated or otherwise, one piece including a sturdy structure embodying side walls, end walls and a bottom, the second piece including an interior assembly of mutually transverse partitions defining a plurality of article receiving compartments and the third piece including distinctive characteristics representative of the contents of the carton on the exterior thereof and embodying side walls, end walls and the particular top closure means.

According to a broad aspect of this invention, there is

2

provided a carton particularly adapted to be stacked in pallets and wherein said pallets are transportable, said carton including a bottom, side walls and mutually opposed end walls, with or without one or two apertures or carrying handholes, and top closure means, said top closure means comprising a pair of closure flaps each said flap being integrally and hingedly connected to an associated one of a pair of mutually opposed walls, each said flap being provided with a plurality of apertures therein, each said aperture having a portion disposed towards the center of a carton adapted to facilitate insertion therethrough and removal therefrom of a crown seal and finish ring of a bottle, a portion of each said flap adjacent to its connection to its associated wall being free of apertures and being adapted to rest upon the top surface of said other mutually opposed walls, the apertured portion of said flaps being adapted to be disposed below the top surface of said other mutually opposed walls, whereby, when bottles are placed in said carton, the crown seals and finish rings thereof are adapted to be passed through said apertures and are adapted to co-operate therewith to lock said closure and to stabilize said bottles within said carton.

According to another aspect of this invention, there is provided in such a carton a bottom structure constituted by an essentially two-ply bottom, single ply mutually opposed side walls, and mutually opposed end walls each provided with a hand carrying aperture, said bottom structure being telescoped within said portion of said carton comprising said mutually opposed side walls, end walls and said top closure means.

In drawings which illustrate embodiments of the present invention,

FIG. 1 is a top plan view of a one-piece blank according to this invention,

FIG. 2 is a perspective view of the carton erected from the blank of FIG. 1, showing the contents therein,

FIG. 3 is a top plan view of another one-piece blank according to this invention,

FIG. 4 is a perspective view of the carton erected from the blank of FIG. 3, showing the contents therein,

FIG. 5 is a top plan view of yet another blank according to this invention,

FIG. 6 is a perspective view of the carton erected from the blank of FIG. 5,

FIG. 7 is a top plan view of still another blank according to this invention,

FIG. 8 is a perspective view of the carton erected from the blank of FIG. 7,

FIG. 9 is a top plan view of an alternative form of a blank according to this invention,

FIG. 10 is a top plan view of a blank adapted for use with the blank of FIG. 9 to form the carton of this invention,

FIG. 11 is a perspective view of the erected blank of FIG. 10,

FIG. 12 is a perspective view of a partially assembled and erected three-piece carton according to this invention, and

FIG. 13 is a central vertical cross-section of an assembled erected three-piece carton according to this invention.

Turning to FIG. 1, the blank indicated generally at 20, comprises three sets of seriatim side-by-side panels 21, 22, and 23. Panels 21 are adapted to form the side and end walls, panels 22 are adapted to form side walls and top closure means, and panels 23 are adapted to form the bottom.

Panels 21 include a pair of side wall panels 24 and 25, a pair of end wall panels 26 and 27, and a tab panel 28. End wall panel 26 is integrally and hingedly connected to

side wall panel 24 along a first fold line 29; side wall panel 25 is integrally and hingedly connected to end wall panel 26 along a second fold line 30; end wall panel 27 is integrally and hingedly connected to side wall panel 25 along a third fold line 31; and tab panel 28 is integrally and hingedly attached to end wall panel 27 along a fourth fold line 32. Each of end wall panels 26 and 27 are provided with a carrying aperture 33 defined by a pair of parallel spaced incisions 34 and 35 joined by semi-circular incisions 36.

Bottom closure panels 23 comprise panels 37, 38, 39 and 40, each integrally and hingedly connected to its associated panels 24, 25, 26 and 27, respectively, along a common fold line 41. It is observed that panel 37 is spaced from panel 39, that panel 39 is spaced from panel 38 and that panel 38 is spaced from panel 40. This is to permit the bottom panels 37 and 38, connected to the side walls 24 and 25 to be folded and then the panels 39 and 40 connected to the end wall to be folded, in erecting the carton, without undue restrictions.

Panels 22 will now be described. Panels 22 include a pair of panels 42 and 43, each adapted to form the second panel of a double thickness side wall, and panels 44 and 45, adapted to form the top closure. Panel 42 is hingedly and integrally connected to panel 24 along a fifth fold line 46, while panel 43 is hingedly and integrally attached to panel 25 along a sixth fold line 47. Panel 42 is provided with an auxiliary panel 48, defined by fifth fold line 46 and a first auxiliary fold line 49 parallel to, and spaced from, said fifth fold line 46. The purpose of auxiliary panel 48 will be explained hereinafter. Similarly, panel 43 is provided with an auxiliary panel 50 defined by sixth fold line 47 and a second auxiliary fold line 51, parallel to and spaced from said sixth fold line 47. The purpose of auxiliary panel 50 will also be described hereinafter. As shown in this embodiment, each of panels 42 and 43 is provided, along their leading edge 52, with a pair of spaced apart tabs 54, although it is, of course, possible to omit such tabs.

Panel 44 is integrally and hingedly attached to panel 25 along a seventh fold line 55, while panel 45 is integrally and hingedly attached to panel 27 along an eighth fold line 56. Panel 44 is subdivided into a primary portion 57, a secondary portion 58 and an auxiliary portion 59 by a pair of parallel spaced apart fold lines 60 and 61, the purpose of portions 58 and 59 to be explained hereinafter. Primary portion 57 is provided with a plurality, in this case three, cut-out portions 62, in which a portion of a sector thereof has a greater radius than the remaining sector. The leading edge 63 of panel 44 is provided with a plurality, in this case three, semi-circular cut-outs 64.

Similarly, panel 45 is subdivided into a primary portion 65, a secondary portion 66 and an auxiliary portion 67 by a pair of parallel, spaced apart auxiliary fold lines 68 and 69, the purpose of portions 66 and 67 to be explained hereinafter. Primary portion 65 is provided with a plurality, in this case three cut-out portions 70, in which a portion of a sector thereof has a greater radius than the remaining sector. The leading edge 71 of panel 45 is provided with a plurality, in this case three semi-circular cut-outs 72.

In erecting the carton from the blank of FIG. 1 as shown in FIG. 2, the panels 21 are folded along fold lines 29, 30, 31 and 32, and tab panel 28 is glued, or otherwise attached to panel 24 to form a rectangular parallelepiped. Bottom panels 37 and 38 are then folded along fold line 41 and panels 39 and 40 are also folded along fold line 41 and folded in overlapping relationship over panels 37 and 38 and glued, or otherwise attached thereto, to form the bottom closure.

Interior side wall panels 42 and 43 are then in-folded along fold lines 46 and 49, and 47 and 51. It is observed that auxiliary panels 48 and 50 are slightly wider than the thickness of the cardboard material, to facilitate the folding. Then, if desired, an interior assembly of mutually transverse partitions defining a plurality of article

receiving compartments may be placed in the opened carton so formed.

The bottles (not shown) containing the beverage are then placed in the carton. It is observed that the height of panels 21 is just slightly greater than the height of the sealed bottles. Top closure panel 44, for example, is folded, along fold line 55, so that secondary portion 58 rests with its side edges on the associated portions of auxiliary panels 48 and 50. Then the cut-outs 62 are mated with the crown seals and finish rings 74 of the bottles so that the crown seals and finish rings 74 only protrude therefrom. The auxiliary panel 59 is of just sufficient width that a step-down portion of the top closure is provided while assuring that only the crown seals and finish rings 74 with their attractive advertising matter thereon is visible, while the necks of the bottles are retained below the top closure, to exclude light from the contents of the bottles. Then panel 45 is folded along fold line 56 so that its secondary portion 66 rests with its side edges on associated portions of auxiliary panels 48 and 50. The cut-out 70 in panel 45 are then mated with the crown seals and finish rings 74 of the bottles as described for cut-outs 62. Then the portion 65 is sprung towards the side wall 27 so that the semicircular cut-outs 72 co-operate with the crown seals and finish rings 74 protruding from cut-outs 62. The natural resiliency of the cardboard assures a relatively tight locking.

Since the cut-outs are formed with a portion of the sector having a radius greater than the radius of the remaining sector, the flaps may readily be opened by having the cut-outs withdrawn from the crown seals and finish rings of the bottles, without tearing the cut-outs. Thus, the carton may be used again, as a multi-trip carton.

Turning to FIG. 3, the blank indicated generally at 120, comprises three sets of seriatim side-by-side panels 121, 122, and 123. Panels 121 are adapted to form the side and end walls, panels 122 are adapted to form side walls and top closure means, and panels 123 are adapted to form the bottom.

Panels 121 include a pair of side wall panels 124 and 125, a pair of end wall panels 126 and 127, and a tab panel 128. End wall panel 126 is integrally and hingedly connected to side wall panel 124 along a first fold line 129; side wall panel 125 is integrally and hingedly connected to end wall panel 126 along a second fold line 130; end wall panel 127 is integrally and hingedly connected to side wall panel 125 along a third fold line 131; and tab panel 128 is integrally and hingedly attached to end wall panel 127 along a fourth fold line 132. Each of end wall panels 126 and 127 is provided with a carrying aperture 133, defined by a pair of parallel spaced incisions 134 and 135 joined by semicircular incisions 136.

Bottom closure panels 123 comprise panels 137, 138, 139 and 140, each integrally and hingedly connected to its associated panel 124, 125, 126 and 127, respectively, along a common fold line 141. It is observed that panel 137 is spaced from panel 139, that panel 139 is spaced from panel 138 and that panel 138 is spaced from panel 140. This is to permit the bottom panels 137 and 138, connected to the side walls 124 and 125 to be folded and then the panels 139 and 140 connected to the end wall to be folded, in erecting the carton, without undue restrictions.

Panels 122 will now be described. Panels 122 include a pair of panels 142 and 143, each adapted to form the second panel of a double thickness side wall, and panels 144 and 145, adapted to form the top closure. Panel 142 is hingedly and integrally connected to panel 124 along a fifth fold line 146, while panel 143 is hingedly and integrally attached to panel 125 along a sixth fold line 147. Panel 142 is provided with an auxiliary panel 148, defined by fifth fold line 146 and a first auxiliary fold line 149 parallel to, and spaced from, said fifth fold line 146. The purpose of auxiliary panel 148 will be explained hereinafter. Similarly, panel 143 is provided with an auxiliary panel 150 defined by sixth fold line 147 and a second auxiliary fold line 151, parallel to and spaced from said

sixth fold line 147. The purpose of auxiliary panel 150 will also be described hereinafter. As shown in this embodiment, each of panels 142 and 143 is provided, along their leading edge 152, with a pair of spaced apart tabs 154, although it is, of course, possible to omit such tabs.

Panel 144 is integrally and hingedly attached to panel 126 along a seventh fold line 155, while panel 145 is integrally and hingedly attached to panel 127 along an eighth fold line 156. Panel 144 is subdivided into a primary portion 157, a secondary portion 158 and an auxiliary portion 159 by a pair of parallel spaced apart fold lines 160 and 161, the purpose of portions 158 and 159 to be explained hereinafter. Primary portion 157 is provided with a plurality, in this case six cutout portions 162, in which a portion of a sector thereof has a greater radius than the remaining sector. The leading edge 163 of panel 144 is provided with a plurality, in this case three, semi-circular cut-outs 164.

Similarly, panel 145 is subdivided into a primary portion 165, a secondary portion 166 and an auxiliary portion 167 by a pair of parallel, spaced apart auxiliary fold lines 168 and 169, the purpose of portions 166 and 167 to be explained hereinafter. Primary portion 165 is provided with a plurality, in this case six, cut-out portions 170, in which a portion of a sector thereof has a greater radius than the remaining sector. The leading edge 171 of panel 145 is provided with a plurality, in this case three, semi-circular cut-outs 172.

In erecting the carton from the blank of FIG. 3 as shown in FIG. 4, the panels 121 are folded along fold lines 129, 130, 131 and 132, and tab panel 128 is glued, or otherwise attached to panel 124 to form a rectangular parallelepiped. Bottom panels 137 and 138 are then folded along fold line 141, and panels 139 and 140 are also folded along fold line 141 and folded in overlapping relationship over panels 137 and 138 and glued, or otherwise attached thereto, to form the bottom closure.

Interior side wall panels 142 and 143 are then in-folded along fold lines 146 and 149, and 147 and 151. It is observed that auxiliary panels 148 and 150 are slightly wider than the thickness of the cardboard material, to facilitate the folding. Then, if desired, an interior assembly of mutually transverse partitions defining a plurality of article receiving compartments may be placed in the opened carton so formed.

The bottles (not shown) containing the beverage are then placed in the carton. It is observed that the height of panels 121 is just slightly greater than the height of the sealed bottles. Top closure panel 144, for example, is folded, along fold line 155, so that secondary portion 158 rests with its side edges on the associated portions of auxiliary panels 148 and 150. Then the cut-outs 162 are mated with the crown seals and finish rings 174 of the bottles so that the crown seals and finish rings 174 only protrude therefrom. The auxiliary panel 159 is of just sufficient width that a step-down portion of the top closure is provided while assuring that only the crown seals and finish rings 174, with their attractive advertising matter thereon is visible, while the necks of the bottles are retained below the top closure, to exclude light from the contents of the bottles. Then panel 145 is folded along fold line 156 so that its secondary portion 166 rests with its side edges on associated portions of auxiliary panels 148 and 150. The cut-outs 170 in panel 145 are then mated with the crown seals and finish rings 174 of the bottles as described for cut-outs 162. Then the portion 165 is sprung towards the side wall 127 so that the semi-circular cut-outs 172 co-operate with the crown seals and finish rings 174 protruding from cut-outs 162. The natural resiliency of the cardboard assures a relatively tight locking.

Since the cut-outs are formed with a portion of the sector having a radius greater than the radius of the remaining sector, the flaps may readily be opened by having the cut-outs withdrawn from the crown seals and finish

rings of the bottles, without tearing the cut-outs. Thus, the carton may be used again, as a multi-trip carton.

Turning to FIG. 5, the blank indicated generally at 220, comprises three sets of seriatim side-by-side panels 221, 222 and 223. Panels 221 are adapted to form the side and end walls, panels 222 are adapted to form side walls and top closure means, and panels 223 are adapted to form the bottom.

Panels 221 include a pair of side wall panels 224 and 225, a pair of end wall panels 226 and 227, and a tab panel 228. End wall panel 226 is integrally and hingedly connected to side wall panel 224 along a first fold line 229; side wall panel 225 is integrally and hingedly connected to end wall panel 226 along a second fold line 230; end wall panel 227 is integrally and hingedly connected to side wall panel 225 along a third fold line 231; and tab panel 228 is integrally and hingedly attached to end wall panel 227 along a fourth fold line 232. Each of end wall panels 226 and 227 are provided with a carrying aperture 223, defined by a pair of parallel spaced incisions 234 and 235 joined by semicircular incisions 236.

Bottom closure panels 223 comprise panels 237, 238, 239 and 240, each integrally and hingedly connected to its associated panel 224, 225, 226 and 227, respectively, along a common fold line 241. It is observed that panel 237 is spaced from panel 239, that panel 239 is spaced from panel 238 and that panel 238 is spaced from panel 240. This is to permit the bottom panels 237 and 238, connected to the side walls 224 and 225 to be folded and then the panels 239 and 240 connected to the end wall to be folded, in erecting the carton, without undue restrictions.

Panels 222 will now be described. Panels 222 include a pair of panels 242 and 243, each adapted to form the second panel of a double thickness side wall, and panels 244 and 245, adapted to form the top closure. Panel 242 is hingedly and integrally connected to panel 224 along a fifth fold line 246; while panel 243 is hingedly and integrally attached to panel 225 along a sixth fold line 247. Panel 242 is provided with an auxiliary panel 248, defined by fifth fold line 246 and a first auxiliary fold line 249 parallel to, and spaced from, said fifth fold line 246. The purpose of auxiliary panel 248 will be explained hereinafter. Similarly, panel 243 is provided with an auxiliary panel 250 defined by sixth fold line 247 and a second auxiliary fold line 251, parallel to and spaced from said sixth fold line 247. The purpose of auxiliary panel 250 will also be described hereinafter. As shown in this embodiment, each of panels 242 and 243 is provided, along their leading edge 252, with a pair of spaced apart tabs 254, although it is, of course, possible to omit such tabs.

Panel 244 is integrally and hingedly attached to panel 226 along a seventh fold line 255, while panel 245 is integrally and hingedly attached to panel 227 along an eighth fold line 256. Panel 244 is subdivided into a primary portion 257 and an auxiliary portion 259 by an auxiliary fold line 260, the purpose of portion 258 to be explained hereinafter. Primary portion 257 is provided with a plurality, in this case three cut-out portions 262, in which a portion of a sector thereof has a greater radius than the remaining sector. The leading edge 263 of panel 244 is provided with a plurality, in this case three, semi-circular cut-outs 264.

Similarly, panel 245 is subdivided into a primary portion 265, and an auxiliary portion 267 by an auxiliary fold line 268, the purpose of portion 266 to be explained hereinafter. Primary portion 265 is provided with a plurality, in this case three cut-out portions 270, in which a portion of a sector thereof has a greater radius than the remaining sector. The leading edge 271 of panel 245 is provided with a plurality, in this case three semicircular cut-outs 272.

In erecting the carton from the blank of FIG. 5 as shown in FIG. 6, the panels 221 are folded along fold

lines 229, 230, 231 and 232, and tab panel 228 is glued, or otherwise attached to panel 224 to form a rectangular parallelepiped. Bottom panels 237 and 238 are then folded along fold line 241 and panels 239 and 240 are also folded along fold line 241 and folded in overlapping relationship over panels 237 and 238 and glued, or otherwise attached thereto, to form the bottom closure.

Interior side wall panels 242 and 243 are then in-folded along fold lines 246 and 249, and 247 and 251. It is observed that auxiliary panels 248 and 250 are slightly wider than the thickness of the cardboard material, to facilitate the folding. Then, if desired, an interior assembly of mutually transverse partitions defining a plurality of article receiving compartments may be placed in the opened carton so formed.

The bottles (not shown) containing the beverage are then placed in the carton. It is observed that the height of panels 221 is just slightly greater than the height of the sealed bottles. Top closure panel 244, for example, is folded, along fold line 255, so that secondary portion 258 rests with its side edges on the associated portions of auxiliary panels 248 and 250. Then the cut-outs 262 are mated with the crown seals and finish rings 274 of the bottles so that the crown seals and finish rings 274 only protrude therefrom.

Because of the location of fold line 260, the primary portion 257 forms an angled-down portion of the top closure while assuring that only the crown seals and finish rings 274, with their attractive advertising matter thereon is visible, while the necks of the bottles are retained below the top closure, to exclude light from the contents of the bottles. Then panel 245 is folded along fold line 256 so that its secondary portion 266 rests with its side edges on associated portions of auxiliary panels 248 and 250. The cut-outs 270 in panel 245 are then mated with the crown seals and finish rings 274 of the bottles as described for cut-outs 262. Then the portion 265 is sprung towards the side wall 227 so that the semi-circular cut-outs 272 co-operate with the crown seals and finish rings 274 protruding from cut-outs 262. The natural resiliency of the cardboard assures a relatively tight locking.

Since the cut-outs are formed with a portion of the sector having a radius greater than the radius of the remaining sector, the flaps may readily be opened by having the cut-outs withdrawn from the crown seals and finish rings of the bottles, without tearing the cut-outs. Thus, the carton may be used again, as a multi-trip carton.

Turning to FIG. 7, the blank indicated generally at 320, comprises three sets of seriatim side-by-side panels 321, 322 and 323. Panels 321 are adapted to form the side and end walls, panels 322 are adapted to form side walls and top closure means, and panels 323 are adapted to form the bottom.

Panels 321 include a pair of side wall panels 324 and 325, a pair of end wall panels 326 and 327, and a tab panel 328. End wall panel 326 is integrally and hingedly connected to side wall panel 324 along a first fold line 329; side wall panel 325 is integrally and hingedly connected to end wall panel 326 along a second fold line 330, end wall panel 327 is integrally and hingedly connected to side wall panel 325 along a third fold line 331; and tab panel 328 is integrally and hingedly attached to end wall panel 327 along a fourth fold line 332. Each of end wall panels 326 and 327 are provided with a carrying aperture 333, defined by a pair of parallel spaced incisions 334 and 335 joined by semi-circular incisions 336.

Bottom closure panels 323 comprise panels 337, 338, 339 and 340, each integrally and hingedly connected to its associated panel 324, 325, 326 and 327, respectively, along a common fold line 341. It is observed that panel 337 is spaced from panel 339, that panel 339 is spaced from panel 338 and that panel 338 is spaced from panel 340. This is to permit the bottom panels 337 and 338, connected to the side walls 324 and 325 to be folded and

then the panels 339 and 340 connected to the end wall to be folded, in erecting the carton, without undue restrictions.

Panels 322 will now be described. Panels 322 include 5 a pair of panels 342 and 343, each adapted to form the second panel of a double thickness side wall, and panels 344 and 345, adapted to form the top closure. Panel 342 is hingedly and integrally connected to panel 324 along a fifth fold line 346, while panel 343 is hingedly and integrally attached to panel 325 along a sixth fold line 347. Panel 342 is provided with an auxiliary panel 348, defined by fifth fold line 346 and a first auxiliary fold line 349 parallel to, and spaced from, said fifth fold line 346. The purpose of auxiliary panel 348 will be explained hereinafter. Similarly, panel 343 is provided with an auxiliary panel 350 defined by sixth fold line 347 and a second auxiliary fold line 351, parallel to and spaced from said sixth fold line 347. The purpose of auxiliary panel 350 will also be described hereinafter. As shown in this embodiment, each of panels 342 and 343 is provided, along their leading edge 352, with a pair of spaced apart tabs 354, although it is, of course, possible to omit such tabs.

Panel 344 is integrally and hingedly attached to panel 25 326 along a seventh fold line 355, while panel 345 is integrally and hingedly attached to panel 327 along an eighth fold line 356. Panel 344 is subdivided into a primary portion 357 and an auxiliary portion 358 by an auxiliary fold line 360, the purpose of portion 358 to be explained hereinafter. Primary portion 357 is provided with a plurality, in this case six cut-out portions 362, in which a portion of a sector thereof has a greater radius than the remaining sector. The leading edge 363 of panel 344 is provided with a plurality, in this case three semi-circular cut-outs 364.

Similarly, panel 345 is subdivided into a primary portion 365, and an auxiliary portion 367 by an auxiliary fold line 368, the purpose of portion 366 to be explained hereinafter. Primary portion 365 is provided with a plurality, in this case six cut-out portions 370, in which a portion of a sector thereof has a greater radius than the remaining sector. The leading edge 371 of panel 345 is provided with a plurality, in this case three semi-circular cut-outs 372.

45 In erecting the carton from the blank of FIG. 7 as shown in FIG. 8, the panels 321 are folded along fold lines 329, 330, 331 and 332, and tab panel 328 is glued, or otherwise attached to panel 324 to form a rectangular parallelepiped. Bottom panels 337 and 338 are then 50 folded along fold line 341 and panels 339 and 340 are also folded along fold line 341 and folded in overlapping relationship over panels 337 and 338 and glued, or otherwise attached thereto, to form the bottom closure.

Interior side wall panels 342 and 343 are then in-folded 55 along fold lines 346 and 349, and 347 and 351. It is observed that auxiliary panels 348 and 350 are slightly wider than the thickness of the cardboard material, to facilitate the folding. Then, if desired, an interior assembly of mutually transverse partitions defining a plurality of article receiving compartments may be placed in the opened carton so formed.

60 The bottles (not shown) containing the beverage are then placed in the carton. It is observed that the height of panels 321 is just slightly greater than the height of the sealed bottles. Top closure panel 344, for example, is folded, along fold line 355, so that secondary portion 358 rests with its side edges on the associated portions of auxiliary panels 348 and 350. Then the cut-outs 362 are mated with the crown seals and finish rings 374 of the bottles so that the crown seals and finish rings 374 only protrude therefrom.

Because of the location of fold line 360, the primary panel 357 is formed into an angled-down portion of the top closure while assuring that only the crown seals and finish rings 374, with their attractive advertising matter

thereon are visible, while the necks of the bottles are retained below the top closure, to exclude light from the contents of the bottles. Then panel 345 is folded along fold line 356 so that its secondary portion 366 rests with its side edges on associated portions of auxiliary panels 348 and 350. The cut-outs 370 in panel 345 are then mated with the crown seals and finish rings 374 of the bottles as described for cut-outs 362. Then the portion 365 is sprung towards the side wall 327 so that the semi-circular cut-outs 372 co-operate with the crown seals and finish rings 374 protruding from cut-outs 362. The natural resiliency of the cardboard assures a relatively tight locking.

Since the cut-outs are formed with a portion of the sector having a radius greater than the radius of the remaining sector, the flaps may readily be opened by having the cut-outs withdrawn from the crown seals and finish rings of the bottles, without tearing the cut-outs. Thus, the carton may be used again, as a multi-trip carton.

Turning to FIG. 9, the blank indicated generally at 420, comprises two sets of seriatim side-by-side panels 421 and 422. Panels 421 are adapted to form the side and end walls, while panels 422 are adapted to form side walls and top closure means.

Panels 421 include a pair of side wall panels 424 and 425, a pair of end wall panels 426 and 427, and a tab panel 428. End wall panel 426 is integrally and hingedly connected to side wall panel 424 along a first fold line 429; side wall panel 425 is integrally and hingedly connected to end wall panel 426 along a second fold line 430; end wall panel 427 is integrally and hingedly connected to side wall panel 425 along a third fold line 431; and tab panel 428 is integrally and hingedly attached to end wall panel 427 along a fourth fold line 432. Each of end wall panels 426 and 427 are provided with a carrying aperture 433, defined by a pair of parallel spaced incisions 434 and 435 joined by semi-circular incisions 436.

Panels 422 will now be described. Panels 422 include a pair of panels 442 and 443, each adapted to form the second panel of a double thickness side wall, and panels 444 and 445, adapted to form the top closure. Panel 442 is hingedly and integrally connected to panel 424 along a fifth fold line 446, while panel 443 is hingedly and integrally attached to panel 425 along a sixth fold line 447. Panel 442 is provided with an auxiliary panel 448, defined by fifth fold line 446 and a first auxiliary fold line 449 parallel to, and spaced from, said fifth fold line 446. The purpose of auxiliary panel 448 will be explained hereinafter. Similarly, panel 443 is provided with an auxiliary panel 450 defined by sixth fold line 447 and a second auxiliary fold line 451, parallel to and spaced from said sixth fold line 447. The purpose of auxiliary panel 450 will also be described hereinafter. Each of panels 442 and 443 is provided, along their leading edge 452, with a pair of spaced apart tabs 454, whose purpose will be described hereinafter.

Panel 444 is integrally and hingedly attached to panel 426 along a seventh fold line 455, while panel 445 is integrally and hingedly attached to panel 427 along an eighth fold line 456. Panel 444 is subdivided into a primary portion 457, a secondary portion 458 and an auxiliary portion 459 by a pair of parallel spaced apart fold lines 460 and 461, the purpose of portions 458 and 459 to be explained hereinafter. Primary portion 457 is provided with a plurality, in this case three cut-out portions 462, in which a portion of a sector thereof has a greater radius than the remaining sector. The leading edge 463 of panel 444 is provided with a plurality, in this case three, semi-circular cut-outs 464.

Similarly, panel 445 is subdivided into a primary portion 465, a secondary portion 466 and an auxiliary portion 467 by a pair of parallel, spaced apart auxiliary fold lines 468 and 469, the purpose of portions 466 and 467 to be explained hereinafter. Primary portion 465 is pro-

vided with a plurality, in this case three, cut-out portions 470, in which a portion of a sector thereof has a greater radius than the remaining sector. The leading edge 471 of panel 445 is provided with a plurality, in this case three semi-circular cut-outs 472.

Turning to FIG. 10, the blank indicated generally at 520, comprises three sets of seriatim side-by-side panels 521, 522 and 523. Panels 521 are adapted to form the side and end walls, panels 522 are adapted to form side walls and panels 523 are adapted to form the bottom.

Panels 521 include a pair of side wall panels 524 and 525, a pair of end wall panels 526 and 527, and a tab panel 528. End wall panel 526 is integrally and hingedly connected to side wall panel 524 along a first fold line 529; side wall panel 525 is integrally and hingedly connected to end wall panel 526 along a second fold line 530; end wall panel 527 is integrally and hingedly connected to side wall panel 525 along a third fold line 531; and tab panel 528 is integrally and hingedly attached to end wall panel 527 along a fourth fold line 532. Each of end wall panels 526 and 527 are provided with a carrying aperture 533, defined by a pair of parallel spaced incisions 534 and 535 joined by generally vertical incisions 536.

Bottom closure panels 523 comprise panels 537, 538, 539 and 540, each integrally and hingedly connected to its associated panel 524, 525, 526 and 527, respectively, along a common fold line 541. It is observed that panel 537 is spaced from panel 539, that panel 539 is spaced from panel 538 and that panel 538 is spaced from panel 540. This is to permit the bottom panels 537 and 538, connected to the side walls 524 and 525 to be folded and then the panels 539 and 540 connected to the end wall to be folded, in erecting the carton, without undue restrictions. It is also observed that, to assist in erecting the carton, circular apertures 575 are provided at the intersections of fold lines 531 with 541, 530 with 541 and 529 with 541. In addition semi-circular apertures 576 are provided at the intersection of fold line 541 with the side edge of panels 524 and 537, and at the intersection of fold line 541 with fold line 532.

Each of panels 539 and 540 have an integral extension 577 thereon of less width than such panels, defining an imaginary slot 578, shown defined by the edges of extension 577 and the dot-and-peck lines. The purpose of this imaginary slot will be described hereinafter.

Panels 522 will now be described. Panels 522 are constituted by a pair of panels 542 and 543, each adapted to form the second panel of a double thickness end wall. Panel 542 is hingedly and integrally connected to panel 526 along a fifth fold line 546, while panel 543 is hingedly and integrally attached to panel 527 along a sixth fold line 547. Panel 542 is provided with an auxiliary panel 548, defined by fifth fold line 546 and a first auxiliary fold line 549 parallel to and spaced from, said fifth fold line 546. The purpose of auxiliary panel 548 will be explained hereinafter. Similarly, panel 543 is provided with an auxiliary panel 550 defined by sixth fold line 547 and a second auxiliary fold line 551, parallel to and spaced from said sixth fold line 547. The purpose of auxiliary panel 550 will also be described hereinafter.

Each of panels 542 and 543 is provided with incised portions adapted to co-operate with carrying apertures 533 in its associated panels 526 and 527 respectively. These incised portions comprise a pair of flaps 578 and 579 divided one from the other by a first common incision 580, and struck from its associated panel by means of second common score line 581 and third common score line 582. Flap 578 is integrally and hingedly attached to its associated panel along fold line 583. It is provided, by fold line 585, parallel to but spaced from fold line 583, with an auxiliary panel 584, whose purpose will be described hereinafter. Similarly, flap 579 is integrally and hingedly attached to its associated panel along fold line 586. It is provided, by fold line 588,

which is parallel to but spaced from fold line 536, with an auxiliary panel 587, whose purpose will be described hereinafter.

In erecting the blank of FIG. 10 as shown in FIGS. 11 and 13, the panels 521 are folded along fold lines 529, 530, 531 and 532, and tab panel 523 is stapled, glued, or otherwise attached to panel 524 to form a rectangular parallelepiped. Bottom panels 539 and 540 are then folded along fold line 541 so that a partial bottom closure is formed. It will be noted that, because of the width of extensions 577 and the presence of imaginary slots 578, there is formed a slot 599 between the side edges of extensions 577 and the adjacent side walls formed by panels 525 and 524. Bottom panels 537 and 538 are then folded along fold line 541 in overlapping relationship exteriorly to panels 537 and 538 and stapled, glued, or otherwise attached thereto, to form the bottom closure.

Inner end walls 542 and 543 are then in-folded along fold lines 546 and 549, and 547 and 551, so that they be generally in face-to-face contact with their associated outer end walls 526 and 527 respectively. A reinforcing bar 589, preferably a wooden strip is placed between inner end wall 542 and outer end wall 526, with its upper edge abutting the inner surface of auxiliary panel 548. Then flaps 578 and 579 are inturned, to be between inner end wall 542 and outer end wall 526 by folding along fold lines 583 and 585 and 586 and 588 respectively, the width of auxiliary portions 584 and 587 respectively being approximately equal to the thickness of the reinforcing bar 589. Then inner end wall 542 is stapled, glued or otherwise attached to outer end wall 526. This results in the provision of a reinforced hand carrying aperture 533.

In a similar manner inner end wall 543 is attached to outer end wall 527.

In erecting the blank of FIG. 9 as shown in FIGS. 12 and 13 the panels 421 are folded along fold lines 429, 430, 431 and 432, and tab panel 428 is glued, stapled, or otherwise attached to panel 424 to form a rectangular parallelepiped. Since there are no bottom panels, an open bottomed carton is formed.

The open-bottomed carton formed by erecting the blank of FIG. 9, is then telescoped over the open-topped carton formed by erecting the blank of FIG. 10, as shown in FIGS. 12 and 13. Thus, side walls 424 and 425 are situated in face-to-face contact exteriorly of side walls 524 and 525 respectively, while end walls 426 and 427 are situated in face-to-face contact exteriorly of side walls 526 and 527 respectively, with hand carrying apertures 433 adapted to register with hand carrying apertures 533.

Side walls 442 and 443 are situated in face-to-face contact interiorly of side walls 542 and 543 respectively, with tabs 454 adapted to register with slots 589. The width of auxiliary panels 448 and 450 is approximately equal to the sum of the thicknesses of the cardboard out of which blanks 420 and 520 are formed, in order to facilitate the folding and erection. Then, an interior assembly 590 of mutually transverse partitions 591 and 592 defining a plurality of article receiving compartments 593 is placed in the erected carton so formed.

The container of FIGS. 12 and 13 is adapted to contain bottles (not shown) containing a beverage. The height of panels 421 and 521 should be just slightly greater than the height of the sealed bottles. Top closure panel 444, for example, is folded, along fold line 455, so that secondary portion 458 rests with its side edges on the associated portions of auxiliary panels 448 and 450. Then the cut-outs 462 are mated with the crown seals and finish rings (not shown) of the bottles so that the crown seals and finish rings only protrude therefrom.

The auxiliary panel 459 is of just sufficient width that a step-down portion of the top closure is provided while assuring that only the crown seals and finish rings with their attractive advertising matter thereon is visible, while

the necks of the bottles are retained below the top closure, to exclude light from the content of the bottles. Then panel 445 is folded along fold line 456 so that its secondary portion 466 rests with its side edges on associated portions of auxiliary panels 448 and 450. The cut-outs 470 in panel 445 are then mated with the crowns 474 of the bottles 473 as described for cut-outs 462. Then the portion 465 is sprung towards the side wall 427 so that the semi-circular cut-outs 472 co-operate with the crown seals and finish rings protruding from cut-outs 462. The natural resiliency of the cardboard assures a relatively tight locking.

Since the cut-outs are formed with a portion of the sector having a radius greater than the radius of the remaining sector, the flaps may readily be opened by having the cut-outs withdrawn from the crown seals and finish rings of the bottles, without tearing the cut-outs. Thus, the carton may be used again, as a multi-trip carton.

Although the present invention has been described for cartons adapted to contain twelve bottles, it is of course possible for any number of bottles to be packaged, providing an appropriate number of cut-out portions is provided in the top closure flaps. In addition while the invention has been described wherein the leading edge of the top closure flaps have semi-circular cut-outs therein, it is also possible to omit such cut-outs. While the cut-outs have been described as having the radius of one sector greater than the radius of the remaining sector other means adapted to permit insertion of the crown seals and finish rings through the cut-out while permitting withdrawal therefrom may be used. Thus, the cut-outs may be oval, or the leading edge may include "starbursts" therein.

In addition, the three-piece embodiment has been described for one type of outer shell. Of course, outer shells adapted from the other embodiments of the carton of the invention shown for example in FIGS. 3-8 may also be used.

I claim:

1. A stackable carton containing bottles said carton adapted to be stacked in pallets and wherein said pallets are transportable, said carton including mutually opposed end walls, side walls, a bottom, a pair of carrying apertures in mutually opposed walls and top closure means, said top closure means comprising a pair of closure flaps each said flap being integrally and hingedly connected to an associated one of a pair of mutually opposed walls, each said flap being provided with a plurality of apertures therein, each said aperture having a portion disposed towards the center of a carton adapted to facilitate insertion therethrough and removal therefrom of a crown seal and finish ring of a bottle, a portion of each said flap adjacent to its connection to its associated wall being free of apertures and being adapted to rest upon the top surface of said other mutually opposed walls the apertured portion of said flaps being adapted to be disposed below the top surface of said other mutually opposed walls, whereby the crown seals and finish rings of bottles placed in said carton are adapted to be passed through said apertures and are adapted to co-operate therewith to lock said closure and to stabilize said bottles.

2. A stackable carton containing bottles said carton adapted to be stacked in pallets and wherein said pallets are transportable said carton including mutually opposed end walls, side walls, a bottom, a pair of carrying apertures in mutually opposed end walls and top closure means, said top closure means comprising a pair of closure flaps each said flap being integrally and hingedly connected to an associated one of a pair of mutually opposed end walls, each said flap being provided with a plurality of apertures therein, each said aperture having a portion disposed towards the center of a carton adapted to facilitate insertion therethrough and removal there-

from of a crown seal and finish ring of a bottle, a portion of each said flap adjacent to its connection to its associated end wall being free of apertures and being adapted to rest upon the top surface of said mutually opposed side walls, the apertured portion of said flaps being adapted to be disposed below the top surface of said mutually opposed side walls, whereby the crown seals and finish rings of the bottles placed in said carton are adapted to be passed through said apertures and are adapted to co-operate therewith to lock said closure and to stabilize said bottles.

3. A stackable carton containing bottles said carton adapted to be stacked in pallets and wherein said pallets are transportable, said carton including mutually opposed end walls, side walls, a bottom, a pair of carrying apertures in mutually opposed end walls and top closure means, said top closure means comprising a pair of closure flaps each said flap being integrally and hingedly connected to an associated one of a pair of mutually opposed end walls, each said flap being provided with a plurality of apertures therein, a sector of each said aperture being of greater radius than the remaining sector of said aperture, said greater radius sector being disposed towards the center of a carton whereby to facilitate insertion therethrough and removal therefrom of a crown seal and finish ring of a bottle, a portion of each said flap adjacent to its connection to its associated end wall being free of apertures and being adapted to rest upon the top surface of said other mutually opposed side walls, the apertured portion of said flaps being adapted to be disposed below the top surface of said mutually opposed side walls, whereby the crown seals and finish rings of bottles placed in said carton are adapted to be passed through said apertures and are adapted to co-operate therewith to lock said closure and to stabilize said bottles.

4. A stackable carton adapted to be stacked in pallets and wherein said pallets are transportable, said carton including mutually opposed end walls, side walls, a bottom, a pair of carrying apertures in mutually opposed walls and top closure means, said top closure means comprising a pair of closure flaps each said flap being integrally and hingedly connected to an associated one of a pair of mutually opposed walls, each said flap being provided with a plurality of apertures therein, each said aperture having a portion disposed towards the center of a carton adapted to facilitate insertion therethrough and removal therefrom of a crown seal and finish ring of a bottle, a portion of each said flap adjacent to its connection to its associated wall being free of apertures and being adapted to rest upon the top surface of said other mutually opposed walls, the apertured portion of said flaps being adapted to be disposed below the top surface of said other mutually opposed walls whereby the crown seals and finish rings are adapted to be passed through said apertures and to co-operate therewith to lock said closure.

5. A stackable carton adapted to be stacked in pallets and wherein said pallets are transportable, said carton including mutually opposed end walls, side walls, a bottom, a pair of carrying apertures in mutually opposed end walls and top closure means, said top closure means comprising a pair of closure flaps each said flap being integrally and hingedly connected to an associated one of a pair of mutually opposed end walls, each said flap being provided with a plurality of apertures therein, each said aperture having a portion disposed towards the center of a carton adapted to facilitate insertion therethrough and removal therefrom of a crown seal and finish ring of a bottle, a portion of each said flap adjacent to its connection to its associated end wall being free of apertures and being adapted to rest upon the top surface of said mutually opposed side walls, the apertured portion of said flaps being adapted to be disposed below the top surface of said mutually opposed side walls whereby the crown seals and finish rings are adapted to be passed through said apertures and co-operate therewith to lock said closures.

6. A stackable carton adapted to be stacked in pallets and wherein said pallets are transportable, said carton including mutually opposed end walls, side walls, a bottom, a pair of carrying apertures in mutually opposed end walls and top closure means, said top closure means comprising a pair of closure flaps each said flap being integrally and hingedly connected to an associated one of a pair of mutually opposed end walls, each said flap being provided with a plurality of apertures therein, a sector of each said aperture being of greater radius than the remaining sector of said aperture, said greater radius sector being disposed towards the center of a carton whereby to facilitate insertion therethrough and removal therefrom of a crown seal and finish ring of a bottle, a portion of each said flap adjacent to its connection to its associated end wall being free of apertures and being adapted to rest upon the top surface of said other mutually opposed side walls, the apertured portion of said flaps being adapted to be disposed below the top surface of said mutually opposed side walls, whereby the crown seal and finish rings are adapted to be passed through said apertures and to co-operate therewith to lock said closure.
